Primary Examiner — Stella M Reid*Assistant Examiner* — Elizabeth J Oswecki(74) *Attorney, Agent, or Firm* — Frijouf, Rust & Pyle, P.A.(57) **CLAIM**

The ornamental design for a fluid container, as shown and described.

DESCRIPTION

FIG. 1 is a front perspective view of a fluid container showing our new design;

FIG. 2 is a rear perspective view FIG. 1;

FIG. 3 is a front view FIG. 1;

FIG. 4 is a rear view FIG. 1;

FIG. 5 is a right side view FIG. 3;

FIG. 6 is a left side view FIG. 3;

FIG. 7 is a top view FIG. 3; and,

FIG. 8 is a bottom view FIG. 3.

The broken line showing of a bottle base in FIG. 8 is included for the purpose of illustrating only and forms no part of the claimed design.
